MULTIPLE SERVICE TAP

William P. Herman, Providence, R. I.

Application October 17, 1938, Serial No. 235,336

8 Claims. (Cl. 173—334)

My present invention relates to electrical multiple service tap devices, and has particular reference to a novel construction and a novel method of assembly of the parts thereof.

5 It is the principal object of my invention to provide a multiple service tap having an integral, one-piece, resilient body.

It is an additional object of my invention to provide a multiple service tap in which the contact prongs may be assembled without use of 10 screws or similar anchoring means.

It is a further object of my invention to provide a novel method of assembly for mounting the contact prongs in the multiple tap, and anchoring 15 the contact prongs within the tap.

It is a further object of my invention to provide a service tap having the cord lead wire effectively anchored to the contact prongs so as to withstand sudden pulls or jerks and to provide 20 strain relief.

Another object of my invention is to provide a multiple service tap in which the body of the tap is shaped to eliminate the danger of short circuiting and arcing.

25 Still another object of my invention is to provide a tap which utilizes resilience of the tap body to ensure the desired contacting engagement of the cooperating prongs, and to secure the contacts within their slots.

With the above and other advantageous features in view, my invention consists of a novel 30 method of assembly and a novel arrangement of parts more fully disclosed in the detailed description following, in conjunction with the accompanying drawings, and more particularly defined in the claims appended hereto.

In the drawings:

Fig. 1 is a front elevation of a multiple service tap employing my invention;

40 Fig. 2 is a side elevation of the same;

Fig. 3 is a bottom view of the same;

Fig. 4 is an enlarged section taken along the line 4—4 of Fig. 1;

45 Fig. 5 is an enlarged section taken along the line 5—5 of Fig. 1;

Fig. 6 is an enlarged section taken along the line 6—6 of Fig. 2;

Fig. 7 is an enlarged edge view of one of the contact prongs;

50 Fig. 8 is an enlarged front view of the same;

Fig. 9 is an enlarged edge view of the other contact prong;

Fig. 10 is an enlarged front view of the same;

Fig. 10a is a perspective view of another form 55 of contact prong;

Fig. 11 is an enlarged plan view of a modified form of contact prong in assembled position;

Fig. 12 is a perspective view of one of the modified form of prongs shown in Fig. 11;

Fig. 13 is a perspective view, partially broken away, of the other contact prong shown in Fig. 11;

Fig. 14 is an enlarged plan view of another form of contact prong in assembled position;

Fig. 15 is a perspective view of one of the blades of the form shown in Fig. 14;

Fig. 16 is a perspective view of the other blades; and

Fig. 17 is an enlarged sectional view, similar to Fig. 6, of a modified form of service tap.

Multiple service taps are conventionally designed to provide three additional places for inserting electrical contact plugs. The conventional taps are designed in various forms, one form for example having three contact portions of the tap fixed to a length of cord lead wire so that an extension plug is provided which can be 20 plugged into the wall and provides three outlets adjacent any electrical equipment, another form having a tap provided with prongs to be plugged into a wall outlet and thus provide three outlets 25 in place of the single wall outlet; there is also a combination of the two in which two outlets and a length of cord are plugged into a wall receptacle.

The form illustrated in Figs. 1 to 6, inclusive 30 of the drawings illustrates applicant's embodiment of the triple outlet, electrical cord connection type, Fig. 17 showing the contact blades displacing the cord lead wire, and Figs. 11 to 16 inclusive illustrating various forms of contact 35 prongs which can be used with any type of tap. Fig. 10a illustrates a preferred type of prong to be used with the combination form above referred to.

Referring to the extension cord form illustrated 40 in Figs. 1 to 6 inclusive, the body portion 20 of the multiple service tap may be of any suitable material, but is preferably molded in one piece of resilient rubber, in any suitable manner, but preferably as described in my copending application, 45 Serial No. 90,042, entitled "Mold constructions for contact plugs," filed July 11, 1936.

The body portion 20 comprises a conical upper portion 21 which receives the electrical cord connection 22, and has three outlet portions disposed in the same plane, outlet 23 opposite to conical portion 21 and outlets 24 and 25 oppositely disposed at right angles thereto. The electrical cord connection 22 may be of any desired length and may have a conventional contact plug 50

at its other end (not shown) for insertion into a wall receptacle. The conical cord receiving portion 21 terminates in an opening 26 which is approximately the diameter of the electrical cord lead wire 22, and is preferably slightly smaller so that a gripping action is obtained on the cord lead wire to relieve the strain on the cord lead wire connection to the contact prongs. The electrical cord connection extends into a cord receiving chamber 27 which diverges into two slots 28 and 29, the resilient rubber body extending between the diverging portions of said slots to form a dielectric baffle 30. The upper ends of the slots 28 and 29 at the base of the baffle 30 are provided with spaced parallel integral projecting portions 31 and 32 having shoulders, which form a restricted passageway portion therebetween (see Fig. 6). Referring to Fig. 4, slots 28 and 29 extend through the plug body, the ends of said slots having shoulders 33 and restricted slot portions 34 forming exit landings.

Extending transversely through the service taps in spaced parallel relation, are slots 35 and 36 terminating in the portions 24 and 25 of the tap body. These slots are so positioned that the central portions thereof cross slots 28 and 29 at right angles to form slightly enlarged slot areas 37 and 38 (see Fig. 4). Slots 35 and 36 are of similar widths to slots 28 and 29 and terminate in restricted slot exit portions 39 and 40 with shoulders 41 and 42 at each end thereof. Each of the intersections of slots 28 and 29 with the slots 35 and 36 is provided with integral, outwardly extending baffle portions 43 and 44 which form restricted combined slot passageway portions 45 and 46.

The tap body heretofore described may be provided with any suitable type of contact prong arrangement, including the types illustrated. Referring to the type shown in Figs. 7 to 10 inclusive, the contact prong 47 comprises a longitudinal blank of electrically conductive metal, having each end thereof bent upon itself, as in Fig. 7, to form wing portions 48 and 49. Each side edge of the blade 47 is provided with spaced, parallel, inwardly extending, oppositely disposed cut-out portions 50 and 51 with shoulders. The main body portion, at each side of the shoulder portions 50 and 51, is provided with oppositely disposed struck-up lugs 52 and 53, and the ends of the wing portions 48 and 49 are also preferably provided with detents 54 for better frictional electrical contact. These contact prongs are adapted to set into the slots 35 and 36.

The prongs which set into the slots 28 and 29 are the prongs to which the cord lead wires are attached. Each prong 55 (see Figs. 9 and 10) comprises a rectangular, electrically conductive blank having one end thereof bent back upon itself to form a double thickness as at 56 and the other end bent back to form a wing portion 57. The center of the blank is provided with a struck-up lug 58, and the end having the wing portion has an opening for assembly purposes. The portion 56 is provided with a transverse slot 59 adjacent the end, and an angularly disposed slot 60 adjacent thereto. Between the struck-up lug 58 and slots 59 and 60 are oppositely disposed, spaced parallel cut-out portions 61 and 62 with abrupt shoulders.

While any method of assembly of the prongs and tap body can be used, I prefer to use the apparatus disclosed in my copending application, Serial No. 99,848, entitled "Connector plug assembly apparatus," filed September 8, 1936, which

matured into Patent No. 2,198,966, issued April 30, 1940.

Referring to Fig. 6, the end of the electrical cord connection is first stripped of insulation and soldered or spot-welded to the upper edge of the blade as shown at 63. The cord is then pulled through the slot 59, over and through the slot 60, back past the slot 59, and out into the cord lead connection. With this construction, the two slots and turns will provide a very powerful and strong anchoring means between the contact prong and the cord lead wire so that strong jerks or pulls cannot dislodge the electrical contact. Moreover, the angle at which the slot 60 is disposed is such that pulling on the cord lead wire 15 locks it in the slot.

In assembling, the contact prongs 47 are first pushed into their slots 35 and 36, either by hand or by machine. When the prongs enter the slots, the first wing portion is bent inwardly by the abutments 43 and 44 until the contact prongs snap by. The prongs then come to rest between each set of shoulder portions 41 and 42, and the abutments 43 and 44 extend towards the body of the prongs between the wing portions 48 and 49 and keep the prongs between the shoulders 41 and 42. The conical portion 21 of the tap body is then stretched or distended, preferably by a machine of the type disclosed in my copending application, hereinbefore referred to, the pull arms of the machine passing through slots 28 and 29 to hook into the openings in the wing portions of the blades 55. The withdrawal of the pull arms pulls each blade into its respective slot 28 and 29 into the position shown in Fig. 6. In this position, the cut-out portions 61 and 62 interlock with the abutments 31 and 32 in the tap body to anchor the prongs in the body. The prongs cross and contact each other in the portions 45 and 46, as shown in Fig. 5, and the abutments 43 and 44 retain the cord connected prong 55 in contact with the blade 47.

To further effectively anchor the blade, the struck-up lugs 58 snap into the cut-out portions 50 (or 51 on the opposite blade which is turned the other way) and the width of the blades 55 fits between the struck-up lugs 52 and 53 on the blade 47. The wing portions 48 and 49 on the blade 47 together with the abutments 43 and 44 effectively retain the blade between each set of shoulders 41 and 42 so that when a contact plug is pushed into the tap, it will not slide behind the prong to pull it away from the wall of the tap body. The upper portions of the prongs 55, to which the cord lead wire is attached, extend into the conical portion 21 of the tap body and are pressed into their respective positions so that they cannot be dislodged by hard use of the service tap.

If desired, the prong 55a, shown in Fig. 10a, can be used instead of the prong 55 so that the service tap may be provided with contact prongs at a point opposite the cord lead connection, for insertion into a wall receptacle. The prong 55a is shown in the solid form to be used in conjunction with the prong shown in Fig. 16 hereinafter to be described; however, the form shown in Fig. 10, prong 55, can be used, modified as in Fig. 10a.

Instead of the prongs 47 and 55, the prong shown in Figs. 11 to 13 inclusive may be used. Referring to Fig. 12, the prong 64 is similar to the prong 55 except that the lug 58 is eliminated and the wing portion 57 is flattened against the prong to form a double thickness of prong with an intermediate, single thickness 65. With this

type of prong, I prefer to use the short cross prong 68 shown in Fig. 13, this cross prong being similar to prong 47 except that there are no cut-out portions and no struck-up lugs, the wing portions 48 and 49 being flattened against the prong but held slightly away from the body of the prong by detents 67. In using this form, the assembly thereof is as shown in Fig. 11, the central one-thickness cut-out portion 65 in blade 64, 10 and portion 68 in blade 66, interlocking to lock the prongs together in their positions in the tap body. The balance of the tap body, including the cut-out shoulder portions, etc., heretofore described is the same, and the method of assembly 15 is similar.

If desired, the prongs may be of solid construction as shown in Figs. 14 to 16 inclusive. In this construction the longer prong 69 is slotted in the upper portion similarly to the prongs 64 and 65, 20 but has a smooth, straight body portion with an extruded opening 70 in the center thereof, formed by punching the opening with a conical die and forcing the edges of the opening upwardly. The short cross prong 71 is offset in its center to form portion 72 and is provided with an opening 73 slightly larger than the circumference of the extruded opening 70. In this construction, assembled as shown in Fig. 14, the indented portion 72 snaps over the edge of the prong 69 and the opening 73 snaps over the extruded portion of the opening 70 to prevent the disengagement of the prongs and to provide an effective lock.

Instead of the tap body used in Fig. 6, the body shown in Fig. 17 may be used. This has four outlet points which are disposed at right angles to each other, the longer prong 74 being provided with protruding contact portions instead of the cable attachment shown in Fig. 6. In this form, the tap is merely plugged into a wall receptacle 40 to provide a plurality of outlets. The form shown in Fig. 17 illustrates the use of a solid blade as shown in Figs. 14 to 16 inclusive. However, any type or form of blade may be used interchangeably with any of the forms herein 45 described or any other standard type of blade not shown.

The use of the above described method of manufacture and assembly provides a multiple service tap with an integral, one-piece body of resilient material, which is easy and economical to manufacture and assemble, the cord lead being very firmly anchored to the contact blade to eliminate danger of short circuiting and arcing, the tap being readily-adapted for different types 55 of multiple service taps such as the forms shown in Figs. 6, 10a, and 17. Moreover, the use of a resilient tap body ensures a better contacting engagement of service plugs, the entrance slots for the service prongs being preferably proportioned to permit the plug body to exert a resilient 60 contacting and holding pressure on the contacting surface of the service plug prongs.

When the service plug prongs are pushed into or pulled out of a conventional multiple service tap, arcing takes place before contact is made and after the contact is broken. Also, when the plug becomes loosened and contact is partially broken, a continuous arcing results. This arcing will burn out the tap, and sometimes causes fires, 65 electrical shocks and burns. By restricting the slot exits, as at 34, 39 and 40, this arcing is substantially eliminated. As the plug blade is pushed into the slot, the restricted portion surrounds and encases the blade in the rubber and 70 prevents arcing until the tip of the blade has 75

almost made direct contact with the service tap blade, thus reducing the arcing to a minimum. Similarly, in withdrawing the plug, the arcing frame is almost immediately snuffed by the dielectric restricted slot portions. Any small amount of arcing is confined to the interior of the plug body immediately surrounding the tip of the blades and this is snuffed before the contact blade is withdrawn. 5

While I have described specific embodiments 10 of my invention, and specific methods for assembly, it is obvious that these are merely illustrative, and that changes in the size and shape of the parts, in the materials used for the parts, their relative arrangement, and in the assembly 15 method followed may be made to suit the requirements for different tap designs, without departing from the spirit and the scope of the invention as defined in the appended claims. 20

I claim:

1. In a multiple service tap, a one-piece body of molded soft resilient material having a plurality of angularly related intercommunicating contact receiving slots extending inwardly from the surfaces thereof, contacts mounted within 25 said slots in electrical and mechanical interlocking engagement with each other, said body constituting yielding resilient means for retaining said contacts within said slots.

2. In a multiple service tap, a one-piece body 30 of molded soft resilient material having a plurality of pairs of angularly related intercommunicating contact receiving slots extending inwardly from the surfaces thereof, pairs of contacts mounted within said slots, one contact of 35 each pair being in electrical and mechanical interlocking engagement with one contact of another pair, said body constituting yielding resilient means for retaining said contacts within 40 said slots.

3. In a multiple service tap, a one-piece body of molded soft resilient material having a plurality of pairs of right-angularly related intercommunicating contact receiving slots extending 45 inwardly from the surfaces thereof, pairs of contacts mounted within said slots, one contact of each pair being in electrical and mechanical interlocking engagement with one contact of another pair, said body constituting yielding resilient 50 means for retaining said contacts within said slots.

4. In a multiple service tap, a one-piece body of molded soft resilient material having a plurality of pairs of right-angularly related intercommunicating contact receiving slots extending 55 inwardly from the surfaces thereof and through said body, pairs of contacts mounted within said slots, one contact of each pair being in electrical and mechanical interlocking engagement with 60 one contact of another pair, said body constituting yielding resilient means for retaining said contacts within said slots.

5. In a multiple service tap, a one-piece body of molded soft resilient material having a plurality of pairs of right angularly related intercommunicating contact receiving slots extending 65 inwardly from the surfaces thereof and through said body, pairs of contacts mounted within said slots, one contact of each pair being in electrical 70 and mechanical interlocking engagement with one contact of another pair, said body constituting yielding resilient means for retaining said contacts within said slots, one pair of contacts extending beyond said body to provide means 75

for establishing electrical energization for all of said contacts.

6. In a multiple service tap, a one-piece body of molded soft resilient material having a plurality of pairs of right angularly related intercommunicating contact receiving slots extending inwardly from the surfaces thereof, pairs of contacts mounted within said slots, one contact of each pair being in electrical and mechanical interlocking engagement with one contact of another pair, said body constituting yielding resilient means for retaining said contacts within said slots, one of each pair of slots being formed to join to provide a cord receiving passage within said body, and a pair of electrical conducting wires extending into said passageway in electrical conducting engagement with one pair of said contacts.

7. In a multiple service tap, a one-piece body of molded soft resilient material having a plurality of angularly related intercommunicating

contact receiving slots extending inwardly from the surfaces thereof, contacts mounted within said slots in electrical and mechanical interlocking engagement with each other, said body constituting yielding resilient means at the intersection of said slots for retaining said contacts within said slots. 5

8. In a multiple service tap, a one-piece body of molded soft resilient material having a plurality of angularly related intercommunicating contact receiving slots extending inwardly from the surfaces thereof, contacts mounted within said slots in electrical and mechanical interlocking engagement with each other, said body constituting yielding resilient means for retaining 10 said contacts within said slots, at least one of said slots being of greater length than the contact therein whereby a flexible slot mouth beyond the end of said contact is provided. 15

WILLIAM P. HERMAN.
